UNITED STATES PATENT OFFICE.

HERMAN J. KLUMPP, OF PORTLAND, OREGON, ASSIGNOR TO BUTTERFIELD BROTHERS, OF SAME PLACE.

DESIGN FOR A HANDLE FOR SPOONS, &c.

SPECIFICATION forming part of Design No. 28,281, dated February 15, 1898.

Application filed October 18, 1897. Serial No. 655,633. Term of patent 7 years.

To all whom it may concern:

Be it known that I, HERMAN J. KLUMPP, a citizen of the United States, residing at Portland, in the county of Multnomah and State 5 of Oregon, have invented and produced a new and original Design for a Handle for Spoons and Similar Articles, of which the following is a specification, reference being had to the accompanying drawings, forming a part there- 10 of, in which—

Figure 1 is a view of the obverse side of a spoon-handle embodying the features of my design, and Fig. 2 is a view of the reverse side of the said handle.

15 The design relates particularly to a handle for such articles as spoons and the like.

On the obverse side of the handle the forward end of the shank is decorated with the conventional scrolls and a marginal rib; but 20 the leading feature of the design at this side of the handle consists of interlaced ribbons, between sundry of which panels are formed containing floral figures. The ribbons forming the panels are carried around the margin 25 of the handle-head, and the shank adjacent to the head of the handle and a portion of the ribbon upon the head are decorated with foli-

ated scrolls, while a foliated crown figure caps the head. On the reverse side the shank of the handle is decorated with scroll and shell figures at its forward end, the margin being ribbed; but the leading feature of the design on this side of the handle consists in imparting to the forward portion of the shank a pillar effect and carrying rearward from the pillar marginal series of connected reversely-curved scrolls. A beaded ribbon figure follows the margin of the head, apparently carried from the obverse side of the handle, while the head is crowned by a cap ornament meet- 30 35 40 ing that upon the obverse side.

I claim—

1. In the design for a handle for spoons and similar articles, the obverse side herein shown and described. 45
2. In the design for a handle for spoons and similar articles, the reverse side herein shown and described.
3. The design for a handle for spoons and similar articles herein shown and described. 50

HERMAN J. KLUMPP.
